UNITED STATES PATENT OFFICE.

PAUL PEBELIER, OF SAN JOSE, CALIFORNIA.

AUTOMOBILE-SIGNAL.

1,187,780.

Specification of Letters Patent. Patented June 20, 1916.

Application filed August 26, 1915. Serial No. 47,542.

To all whom it may concern:

Be it known that I, PAUL PEBELIER, a citizen of the United States, and resident of San Jose, in the county of Santa Clara and State of California, have invented a certain new and useful Improvement in Automobile-Signals, of which the following is a specification.

My invention relates to an alarm and illuminated sign signal, and the objects of my invention are to produce a device of the character indicated, 1st, which can be readily positioned in an automobile in such a manner as to be plainly visible to the drivers of machines in the rear both by day and night; 2nd, that can be easily adapted to be operated by the hand or foot of the driver of the machine in which it is placed; 3rd, that provides means for calling the attention of drivers in the rear of the machine to the sign displayed; 4th, that can be caused to display any one of a number of signs at the will of the driver; 5th, that will produce a clearly audible sound during the whole period of time in which a sign is displayed; 6th, that will automatically stop the sound when the sign is withdrawn; 7th, that will automatically illuminate the sign during the whole period of time in which it is displayed; 8th, that will be simple in construction, easy of operation, and inexpensive to manufacture. I attain these objects by the mechanism illustrated in the accompanying drawings, in which,—

Figure 1 is a perspective view of an automobile with my device in position, parts being broken away. Fig. 2 is a plan view of my device with the top removed and operating mechanism not shown. Fig. 3 is a vertical section of my device on line A—A of Fig. 2, with the top on. Fig. 4 is a detail elevation of the operating lever. Fig. 5 is a sectional view on line B—B of Fig. 3. Fig. 6 is a detail perspective showing a mounted roller. Fig. 7 is a detail perspective of a bracket showing method of mounting one spring wire. Fig. 8 is a perspective view of my device with batteries connected.

Similar reference characters refer to similar parts throughout the several views.

The subject matter of this invention naturally falls into three divisions: first the sign proper, second the illuminating means, and third the alarm. Taking these divisions

in their order, the sign, together with the receptacle and the operating mechanism, will be described first.

Referring now more particularly to the drawings, 1 indicates a receptacle preferably having a removable top and front made in one piece and provided with an aperture 2^a fitted with a piece of transparent material as 2^b. Receptacle 1 has a shaft 3 journaled in the forward portion thereof in approximately the position shown, said receptacle 1 being secured in the desired position by bolts or screws through holes as 1^a and 1^b in lugs 1^c and 1^d. Secured near each end of said shaft 3 is a wheel 4, having a groove 5 formed therein.

In groove 5 of one of said wheels 4 is secured a metallic plate as shown at 6, the ends of said plate 6 being spaced apart as indicated at 7. Mounted upon wheels 4 in such a manner as not to obstruct groove 5 is a sheet of transparent material, as celluloid, shown at 8. This transparent sheet 8 is of such a length as to permit the signs shown thereon to be successively thrown into view as hereinafter described. In the drawing the sheet 8 is shown extending from point 9 to point 10, and has four signs outlined thereon, viz.,—two arrows 11 and 12 pointing in opposite directions, and the words "Slow" as shown at 13, and "Stop" as shown at 14.

As a means of revolving the sign on shaft 3 and returning the same to its original position, the following mechanism is provided: Two bars, 15 and 16, are secured to shaft 3 a distance apart and off center. The shorter arms of bars 15 and 16 are joined by a rod 17 journaled therein, rod 17 being connected to the back of receptacle 1 by tension springs 18 and 19 respectively, revolvably connected thereto and to pins 20 and 21 mounted in brackets 22 and 23 which are in turn secured to said back of said receptacle 1. The long arms of bars 15 and 16 are joined by rod 24 journaled therein. Attached to rod 24 is a wire 25, the same passing rearwardly and out through the back of receptacle 1 through flexible conduit 26. Conduit 26 passes through a block 27 secured to receptacle 1 and is fastened therein by set screw 28. Conduit 26 is passed to the forward portion of the machine 37 where wire 25 is allowed to emerge and is secured

to a lever as 29. Lever 29 is pivotally mounted at 30 on circular ratchet 31, which is bolted to the machine through holes 32. Lever 29 is provided with a catch 33 pivotally mounted thereon at 34 and having a spring, as 35, positioned in approximately the position shown. Wire 25 being passed through conduit 26 will operate freely when once properly adjusted. An aperture, as 36, of the proper length and width to fully expose a single sign when thrown into position is provided in the desired location in the rear wall of the automobile 37, and receptacle 1 rigidly mounted in position behind said wall and beneath the rear seat 37^a of said automobile 37, so that any one of the signs may be thrown into register with said aperture 36.

When in a normal position sheet 8 is in the position shown in Fig. 3, and catch 33 on lever 29 is in the position indicated at 38. When catch 33 is thrown over and caught in notch 31^b, arrow 11 is drawn upward into position and registers with aperture 36, thus advising drivers in the rear that the machine is about to turn to the right. The new positions assumed by the movable parts in this operation are indicated by the center lines 25^a, 16^a and 19^a. When catch 33 is forced into notch 31^b arrow 12 is drawn into position, thus advising drivers in the rear that the machine is about to turn to the left. When catch 33 is forced successively into notches 31^c and 31^d, the words "Slow" and "Stop" successively register with aperture 36 and indicate the action about to be taken by the driver of the machine. Catch 33 is thrown at once into the proper notch to bring the sign desired into view. Upon withdrawing catch 33 from the notch in which it may be positioned and moving lever 29 back to the normal position indicated by the center line shown at 38, springs 18 and 19 at once cause the signs to revolve back to a normal position out of sight.

The alarm and illumination portions of my device co-act with the sign proper, and consequently (being operated by an electric current) are placed on the same circuit, 50 which is closed and opened by the operation of the sign exposing and retracting mechanism. The illumination is secured by an electric incandescent bulb 40 set in socket 41, which is in turn securely screwed to the back 55 of receptacle 1 by screws 42 and 43. An electrically operated bell is positioned substantially as shown at 44, the same being screwed to the bottom of receptacle 1 by screw 45.

60 46 and 47 refer to the two binding posts on bell 44, and 48 and 49 refer to the two contact screws of bulb 40, while 50 and 51 refer to the terminals of battery 52.

At 53 is shown a binding post secured to 65 the bottom of receptacle 1 and insulated

therefrom by insulator 54. A spring wire 55 is connected to said binding post 53 and carried through said insulator 54 and terminates in groove 5 of wheel 4. The end of wire 55 is forked as shown at 56 and has a 70 roller as 57 revolvably mounted therein on pin 58. These parts 55, 57 and 58, are conductors of electricity.

Secured to the back of receptacle 1 near the upper edge thereof, and insulated therefrom, and in the same vertical plane as the wheel 4 to which wire 55 is connected, is securely fastened a bracket 59 by screws 60 and 61. Passing horizontally through bracket 59 is pin 62. Spring wire 63 is securely fastened to pin 62 and passes out through hole 64 in the front portion of bracket 59, curves upwardly and terminates in groove 5 in the top of wheel 4. The end of wire 63 is also forked as shown at 66^a and 85 provided with a roller 57^a as described in connection with wire 55. These parts 59, 62, 63 and roller 57^a are conductors of electricity.

Secured to the back of receptacle 1 and 90 near the bracket 59 is binding post 65, which is electrically connected to bracket 59 by insulated wire 66. Binding post 65 is connected to terminal 51 of battery 52 by wire 67, and binding post 47 on bell 44 is connected to terminal 50 of battery 52 by wire 68. Binding post 47 of bell 44 is also connected to contact screw 48 of bulb 40 by wire 69. Contact screw 49 of bulb 40 is connected to binding post 46 of bell 44 by wire 70, and 100 binding post 46 of bell 44 is connected to binding post 53 by wire 71.

With the signs in a normal retracted position neither the bulb or bell are in operation as the roller on the end of wire 63 rests on 105 wheel 4 in space 7 between the ends of metallic plate 6. When any one of the signs is thrown into view as hereinbefore described, the revolving of wheel 4 causes the roller on wire 55 to come in contact with 110 plate 6, whereupon the circuit is completed and light is produced in bulb 40 and bell 44 is caused to ring. The complete closed circuit beginning with plate 6 is as follows:— plate 6, roller 57, pin 58, wire 55, binding 115 post 53, wire 71, binding post 46, bell 44, binding post 47, wire 68, terminal 50, battery 52, terminal 51, wire 67, binding post 65, wire 66, bracket 59, pin 62, wire 63, pin and roller on the end of wire 63 and again 120 plate 6. The bulb 40 is placed on the same circuit by being connected to binding posts 46 and 47 of bell 44 as hereinbefore described.

It may thus be seen that if a driver is 125 about to change the direction or speed of his machine he may announce that fact to drivers in the rear by displaying the appropriate sign, this action automatically illuminating the sign and ringing the bell to call 130

attention to the same, the bell also serving to remind the driver to return the sign to its normal position after the proposed action has been taken.

5 It is not my desire to be limited to the exact construction of my device as described in this specification, as many minor changes in construction and operation may be made without departing from the spirit of my invention. My device may be also used on the outside of a machine as shown at 72 in dotted lines, or in any position where the signal can be readily seen by the drivers of following machines, and of course the 10 electric current may be derived from a magneto instead of a battery.

Having thus described my invention, what I claim as new and desire to secure by Letters Patent, is,—

20 1. A signal system comprising a case, a sign carrying frame having circular end pieces revolvably mounted therein, means for revolving said frame a predetermined distance in one direction, means for securing said frame in said revolved position, means for returning said frame to its normal position, a metallic plate having its ends spaced a distance apart secured to the outer circumference of one of said end pieces, an electric bell mounted in said case, an electric light 25 mounted in said case, an electricity generator, and means for operatively connecting said bell, said light, said generator and said metallic plate in the same circuit.

25 30 2. A signal system comprising a case, a sign carrying frame having circular end pieces revolvably mounted therein, means for revolving said frame a predetermined distance in one direction, means for securing said frame in said revolved position, means for returning said frame to its normal position, a metallic plate having its ends spaced a distance apart secured to the outer circumference of one of said end pieces, an electric bell mounted in said case, an electric light mounted in said case, an electricity generator, and means for operatively connecting said bell, said light, said generator and said metallic plate in the same circuit.

said bell, light, generator, and metallic plate in the same circuit.

2. A signal system comprising a case, a 35 sign carrying frame having circular end pieces revolvably mounted therein, means for revolving said frame a predetermined distance in one direction, means for securing said frame in said revolved position, means 40 for returning said frame to its normal position, a metallic plate having its ends spaced a distance apart secured to the outer circumference of one of said end pieces, a spring wire mounted in said case and 45 having a roller mounted on its free end, said roller normally resting on the circumference of said end piece between the ends of said metallic plate, a second spring wire mounted on said case having a roller mounted on its free end, said roller being in constant contact with said metallic plate, an electric bell mounted in said case, an electric light mounted in said case, an electricity generator, and means for operatively connecting said bell, said light, said generator and said metallic plate in the same circuit.

In testimony whereof I have hereunto affixed my signature in presence of two subscribing witnesses.

PAUL PEBELIER.
